United States Patent Office.

ISRAEL PUTNAM MAGOON, OF ST. JOHNSBURY, VERMONT.

Letters Patent No. 101,287, dated March 29, 1870.

FEED-WATER HEATER FOR LOCOMOTIVES.

The Schedule referred to in these Letters Patent and making part of the same.

To all persons to whom these presents may come:

Be it known that I, ISRAEL PUTNAM MAGOON, of St. Johnsbury, of the county of Caledonia, of the State of Vermont, have made a new and useful invention or Improvement in Locomotive Steam-Engines; and do hereby declare the same to be fully described in the following specification and represented in the accompanying drawings, of which—

Figures 1 and 2 are vertical sections of the smoke-box and chimney of a locomotive engine with my invention applied thereto.

Figure 3 is a top view of the saddle at the bottom of the chimney.

This saddle A, instead of being formed in the ordinary manner, viz., with a flat horizontal bottom, has two semicircular depressions or cavities, *a a*, arranged on opposite sides of the steam-chimney B, which goes through and is led upward from the saddle and opens out of the smoke-arch or box C.

The bottoms *b b* of these cavities are inclined in opposite directions, and there is an opening, *c*, made through the side of the steam-chimney, so as to lead from each cavity *a* into it.

The exhaust-pipe is shown at D, and the smoke or steam-chimney at E. The latter rests directly on the saddle and is arranged concentrically with the steam-chimney.

The said steam-chimney B is surmounted by a deflecting-bonnet, F, which serves to throw or deflect downward into a hollow conical frustum, G, open both at top and at bottom, which encompasses the steam-chimney, and is arranged in the smoke-chimney, in manner as represented, the steam and smoke which may escape from the top of the steam-chimney.

Within the said frustum G is a helical coil of pipe, H, whose ends open through the lower part of the smoke-chimney.

One terminus of the coil is to communicate with the boiler, and the other with the force-pump of the engine, the same being so as to cause the water from

the tank, in its passage to the boiler, to be heated by the coil exposed within the frustum G to the smoke and steam which may be thrown therein.

There is a space, *s*, around the coil and between it and the frustum G, the same being to enable the smoke and the waste steam deflected into the frustum to freely act on the outer surface of the coil.

The steam driven into the exhaust-pipe passes with the smoke directly into the steam-chimney, and striking the deflector at its top, will be deflected downward into the frustum G and against the coil and out of the lower end of the frustum G, the smoke and steam will rush into and up through the smoke-chimney or space around the frustum G, and thence through the wire netting or cap I of the top of the said chimney.

Any sparks or cinders which may fall down upon the saddle, or into either of the cavities *a a* thereof, will be drawn out of the cavity and through its escape-hole *c*, the position of the said escape-holes being such as to prevent the steam from being driven through them while passing from the exhaust-pipe into the chimney or flue B.

The cinders which may escape through the openings *c c* will fall into the smoke-box or finally be consumed.

By means of the internal frustum G, arranged and combined with the outer or smoke-chimney, the steam-chimney, the deflector, and the coil, such coil will be heated to better advantage than it would be were there no such internal frustum about it and in the main chimney.

I therefore claim as my invention the arrangement and combination of the internal frustum G with the steam-chimney or pipe B, the deflector F, the heating-coil H, and the main or smoke-chimney E.

I. P. MAGOON.
